UNITED STATES PATENT OFFICE.

ARTHUR D. CHILDS, OF NORTH BRADLEY, MICHIGAN.

SHIPPING-CRATE.

1,242,143.

Specification of Letters Patent.

Patented Oct. 9, 1917.

Application filed June 30, 1917. Serial No. 177,904.

To all whom it may concern:

Be it known that I, ARTHUR D. CHILDS, a citizen of the United States, residing at North Bradley, in the county of Midland 5 and State of Michigan, have invented certain new and useful Improvements in Shipping-Crates, of which the following is a specification, reference being had to the accompanying drawings.

10 This invention relates to certain improvements in shipping crates and has relation more particularly to a device of this general character of a collapsible type and it is an object of the invention to provide a device 15 of this general character having novel and improved means whereby the same may be effectively maintained in an extended or operative position or in a collapsed or compacted adjustment.

20 It is also an object of the invention to provide a novel and improved device of this general character including a top panel and a bottom panel together with side panels 25 operatively engaged with the top and bottom panels whereby relative separating movement between the top and bottom panels results in the side panels being extended.

It is also an object of the invention to provide a novel and improved device of this 30 general character wherein swinging end panels are employed together with co-acting means carried by said swinging end panels and the top panel for locking the crate in its extended or operative adjustment.

35 A still further object of the invention is to provide a novel and improved device of this general character including relatively movable top and bottom panels together with co-acting means carried by the top 40 and bottom panels for locking the same in collapsed or compacted adjustment.

The invention consists in the details of construction and in the combination and arrangement of the several parts of my improved shipping crate wherein certain important advantages are attained and the device rendered simpler, less expensive and otherwise more convenient and advantageous for use, as will be hereinafter more 50 fully set forth.

The novel features of my invention will hereinafter be definitely claimed.

In order that my invention may be the better understood I will now proceed to describe the same with reference to the accompanying drawings, wherein—

Figure 1 is a view in top plan with por-

tions broken away of a crate constructed in accordance with an embodiment of my invention and in extended or operative adjustment; 60

Fig. 2 is a view partly in side elevation and partly in section of my improved crate in a folded or compacted adjustment;

Fig. 3 is a sectional view taken substantially on the line 3—3 of Fig. 2;

Fig. 4 is a longitudinal vertical sectional view taken through the device as illustrated in Fig. 1;

Fig. 5 is an end elevational view of my 70 improved crate as herein disclosed in extended adjustment; and

Fig. 6 is a transverse sectional view taken through the device in extended adjustment.

While my improved device as herein illustrated is of a type especially designed for use in the shipping of poultry or the like it is to be understood that I do not desire to limit myself to this particular character of crate. 75

As disclosed in the accompanying drawings B denotes the bottom panel of my improved crate of predetermined dimensions and preferably rectangular in plan. The marginal portions of the bottom panel B 80 are defined by the cleats 1 secured to the upper face of the bottom panel B.

Hingedly connected as at 2 with the side cleats 1 are the side panels S which, when in open or extended position overlie the top 90 faces of the side cleats 1. The outer longitudinal marginal portion of each of the side panels S adjacent opposite ends thereof is provided with the clips 3 and said clips are directed through the transversely disposed 95 slots 4 arranged adjacent the opposite ends of the top panel T. The clips 3 overlie marginal portions of the slots 4 whereby it will be perceived that upon relative movement between the bottom panel B and the top 100 panel T, the side panels S will be either extended or folded.

E denotes end panels having their lower margins hingedly connected as at 5 with the bottom panel B at a predetermined point 105 inwardly of the end cleats 1, so that said end panels when in extended or open position will contact with the end cleats 1 as particularly illustrated in Fig. 4 of the accompanying drawings. The top panel T 110 has its marginal portion defined by the inwardly directed flanges afforded by the cleats 6 and the open or extended position of the side panels S is limited by the con-

tact of said side panels with the inner faces of the side or longitudinal flanges or cleats 6 while the open or extended movement of the end panels E is limited by the contact 5 of said panels E with the end or transverse flanges or cleats 6. It will also be understood that the end panels E when in open or extended position serve to maintain the side panels S in their open or extended adjustment.

The outer or free longitudinal margin of each of the end panels E is provided with a pair of outwardly and laterally directed arms 7 terminating in the inwardly directed 15 extensions 8. The arms 7 with the extensions 8 thereof are directed through the slots 9 produced in the adjacent end flange or cleat 6 of the top panel T. Slidably supported by the outer face of the end flange 20 or cleat 6 is the locking member L which moves transversely of the flange or cleat 6 and has an intermediate depressed portion 10 adapted to underlie the inwardly directed extensions 8 whereby the end panel E is 25 effectively held against inward or folding movement. The end portions of the locking member L are provided with perpendicularly related extensions 11 disposed through the guiding eyes 12. The free end 30 portions of the extensions 11 are formed into the hook members 14 preferably inwardly directed and which serve to prevent the displacement of the locking member L. To hold the locking member L against movement to disengage the same from the inwardly directed extensions 8 the wire seal 15 or its equivalent may be employed as illustrated particularly in Fig. 5 and wherein said seal is operatively engaged with the intermediate portion 10 of the locking member L and threaded through the eye member 16 carried by the end flange or cleat 6. When the crate is compacted or folded the hook members 17 pivotally engaged with 45 the side or longitudinal cleats or flanges 1 are engaged with the top panel T and preferably overlie said top panel T as particularly illustrated in Fig. 2 as said hook members 17 are of such a length as to extend through the openings in the top panel T as afforded in the present embodiment of my invention by the transverse separated strips 18. The members 17 are maintained in operative engagement with the top panel 50 T through the medium of the arms 19. Each of the arms 19 is pivotally engaged at one end with the outer face of a side or longitudinal flange or cleat 6 with the top panel T and has its opposite end portion 55 terminating in the lateral extension 20 to

engage rearwardly of a hook member 17 and thereby hold the same against disengagement from the top panel T.

From the foregoing description, it is thought to be obvious that a shipping crate 65 constructed in accordance with my invention is particularly well adapted for use by reason of the convenience and facility with which it may be assembled and operated and it will also be obvious that my invention is 70 susceptible of some change and modification without materially departing from the appearance and spirit thereof and for this reason I do not wish to be understood as limiting myself to the precise arrangement and 75 formation of the several parts herein shown in carrying out my invention in practice except as hereinafter claimed.

What I claim is:

1. A device of the character described 80 comprising a bottom panel, side panels hingedly connected thereto, a top panel, means for slidably connecting the side panels with the top panel, end panels hingedly connected with the bottom panel 85 and interposed between the side panels when said side panels are extended, arms carried by the end panels and provided with lateral extensions, the ends of the top panels being provided with slots through which said arms 90 and angular extensions are directed, and locking members carried by the top panel to underlie the lateral extensions of the arms of the end panels for holding said end panels against inward movement.

2. A device of the character described comprising a bottom panel, side panels hingedly connected thereto, a top panel, means for slidably connecting the side panels with the top panel, end panels hingedly 100 connected with the bottom panel and interposed between the side panels when said side panels are extended, arms carried by the end panels and provided with lateral extensions, the ends of the top panel being 105 provided with slots through which said arms and angular extensions are directed, and locking members carried by the top panel to underlie the lateral extensions of the arms of the end panels for holding said end panels against inward movement, and means co-acting with the locking members 110 for holding the same in operative engagement with the arms of the end panels.

In testimony whereof I hereunto affix my 115 signature in the presence of two witnesses.

ARTHUR D. CHILDS.
